DESIGN FOR A CHAIR

Marguerite F. Minard, Seattle, Wash.

Application October 2, 1939, Serial No. 87,482

Term of patent 7 years

To all whom it may concern:

Be it known that I, Marguerite F. Minard, a citizen of the United States, residing at Seattle, King County, Washington, have invented a new, original, and ornamental Design for a Chair, of which the following is a specification, reference being had to the accompanying drawing, forming a part thereof, wherein the single figure is a perspective view of a chair embodying the present design.

The drawing shows the front and one side of the chair, and the side shown is substantially the same as the opposite side.

I claim:

The ornamental design for a chair, as shown and described.

MARGUERITE F. MINARD.
